UNITED STATES PATENT OFFICE.

HUMPHREYS O. SIEGMUND, OF WEST ORANGE, NEW JERSEY, ASSIGNOR TO WESTERN ELECTRIC COMPANY, INCORPORATED, OF NEW YORK, N. Y., A CORPORATION OF NEW YORK.

ELECTROLYTIC CELL.

Application filed October 22, 1924. Serial No. 745,049.

This invention relates to electrolytic cells and has for an object the provision of a supporting member for mechanically weak electrodes.

5 The invention has particular application to a metallic support for tin cathodes in electrolytic cells, though it is not limited to this application alone.

It is commonly known that in electrolytic 10 condensers the electrode members should be composed of some metallic composition which is substantially inert to the destructive chemical action of the electrolyte employed. The anodes in such pieces of apparatus are usually composed of some film-forming metal, such as aluminum, for example. When used across circuits of unidirectional and pulsating potential, the cathode members of such cells should be composed of 15 a composition which, when the current density on the cathode surface is high, is not only inert to the action of the electrolyte, but which is also a non-film forming material. For this purpose tin has been found to be 20 satisfactory. Because of the non-rigid character of tin, however, it has been found desirable, in accordance with the invention, to mechanically strengthen electrodes composed of tin by supporting them in the cell with 25 elements having a rigid character.

30 From a mechanical viewpoint metals, of course, form the most desirable material for use as supporting elements. It is known, however, that when a mechanical joint between metallic elements is immersed in an electrolyte, a corrosion of the metals is 35 likely to result. In time, this corrosion may reach such a depth that the metals become consumed at the joints. Furthermore, this 40 corrosion has been found to increase the watt loss by increasing the resistance of the joints.

45 One cause of such corrosion has been found to be the local or galvanic action which is characteristic in joints between metals. This galvanic action has in turn been found to be due to the difference between the absolute potentials of the metals and it is generally believed that the corrosion or galvanic action varies directly with this difference between the absolute potentials. 50 Thus, between elements which are near together in the so-called electro-motive series of elements—an arrangement of elements in accordance with their absolute potentials—

there will be a smaller galvanic action set up and therefore less corrosion caused than between those metals which are far apart. It has been found, however, that even the small reverse current set up between metals close together in the electro-motive series 60 results in an undesirable corrosion when employed in electrolytic condensers.

Further, any metal used as a supporting element for cathode members in electrolytic condensers should be substantially unattacked by the electrolyte employed. The invention provides, therefore, a method for and means of joining a wide range of metals, without the presence of the undesirable 70 corrosion or galvanic action described above.

A fuller understanding of the invention will be obtained from the more detailed description to follow.

In the accompanying drawings in which similar parts are indicated in the several figures by the same reference characters, Fig. 1 is a side view, along the line 1—1 of Fig. 3, of a cell employing the supports of this invention. Fig. 2 is an end sectional view, along the line 2—2 of Fig. 1. Fig. 3 is a top view, along the line 3—3 of Fig. 2.

An electrolyte 4 is contained in an insulating casing 5 over which a cover 6 is fitted. Anodes 7 composed of a film forming composition, aluminum, for example, are 85 suspended from a cover and between suitable cathodes 8, such as tin, for example. The cathodes are supported in accordance with this invention by supporting members 9 suspended from the cover and composed of a film-forming composition which is electro-positive to the composition of the cathode, such as aluminum, for example. The cathodes may be mechanically joined to the supports by rivets 10 which may also be 90 composed of the composition forming the support. The use of mechanical joints has been found to be more satisfactory than welded or soldered joints in that harmful impurities in the form of fluxes are not thus 95 introduced into the electrolyte.

It has been found that the usual corrosion existing in metallic joints is substantially 100 eliminated when film-forming metals are joined to metals which are electro-negative to them; for example, aluminum, as a film-forming metal, may be joined without corrosion to tin, which is electro-negative to it.

This elimination of corrosion in joints between film-forming metals and metals electro-negative to them is believed to be due to the dielectric film formed on the film-forming metal when it is an anode in any cell, such as that formed, for example, when it is joined in an electrolyte to metal electro-negative to it. It is known that this film in time becomes heavy enough to appreciably retard the flow of a current from the film-forming metal into the electrolyte although not appreciably affecting the flow of current from the electrolyte to the film-forming metal. Such a film would, therefore, hinder any tendency for a current to flow from aluminum, for example, to metal electro-negative to it in a joint composed of the two metals; and would, therefore, retard corrosion in such a joint. Actual practice has shown that such supports constitute a satisfactory and practical means of supporting mechanically weak electrodes which are electro-negative to the supports, extended tests over periods of many months having been made with no signs of corrosion at the joint of electrode and electrode support.

Any film-forming composition such as tantalum or magnesium, for example, is, of course, suitable for use to eliminate corrosion in joints and it will, therefore, be appreciated that the invention is not to be restricted to the use of aluminum. 30

While the invention has been illustrated specifically in connection with supports for tin cathodes in electrolytic cathodes, it will 35 be appreciated that it is not intended to impose any restrictions upon the application of the invention other than those set forth in the claims, but that the invention may be employed to eliminate corrosion in a wide 40 range of joints.

What is claimed is:

In an electrolytic condenser, a casing, a film forming electrolyte within said casing, tin electrodes immersed in said electrolyte 45 and means for supporting said electrodes, said means comprising aluminum supports.

In witness whereof, I hereunto subscribe my name this 15th day of October, A. D. 1924.

HUMPHREYS O. SIEGMUND.
